UNITED STATES PATENT OFFICE.

PERRY O. BROWN, OF ST. VINCENT, MINNESOTA.

AUTOMATIC RAILWAY SWITCH.

Application filed April 24, 1924. Serial No. 708,713.

To all whom it may concern:

Be it known that I, PERRY O. BROWN, a citizen of the United States, residing at St. Vincent, in the county of Kittson and State 5 of Minnesota, have invented certain new and useful Improvements in Automatic Railway Switches, of which the following is a specification.

This invention relates to automatic rail- 10 way switches and it consists in the novel features hereinafter described and claimed.

An object of the invention is to provide a railway switch structure adapted to be operated by electromagnets which may be 15 energized by an electric circuit which is closed by an engine moving upon the railway, the electric current being supplied to the circuit, by a generator, which is carried by the engine, or which may be located 20 upon any other object or at any fixed point.

With the above objects in view, the structure includes a bridle bar, which is connected with the movable rail sections of the track and switch, with spring means for 25 holding the bar, so that the movable track rail section, is normally held in alignment with one of the rails of the track, thus closing the switch. Two magnets are positioned adjacent the track, and one of them 30 is connected in open circuit with conductors, which extend along the track. The other is electrically connected with the said conductors, and one of the movable switch rails. Levers are arranged to be swung by 35 the said magnets when they are energized, and one of the said levers is connected with a circuit closer, which connects with the second mentioned magnet. Both of the said levers are operatively connected with block 40 and tackle means adapted to serve as means for moving the bridle bar and with which they are connected.

In the accompanying drawings:—

Figure 1 is a perspective view of the 45 switch structure and adjacent parts.

Figure 2 is a top plan view of the switch.

Figure 3 is a fragmentary perspective 50 view of the locomotive cab, showing trolley means mounted thereon, and adapted to engage the conductors which are disposed along the tracks.

Figure 4 is a fragmentary rear elevation of the locomotive cab.

As illustrated in the drawings, the track 55 rails are indicated at 1, and the switch rails are indicated at 2. Movable points

3 and 4 are provided, at the intersection of the switch with the tracks, and are of usual arrangement. A bridle bar 5 is disposed transversely of the track 1 and is connected with the points 3 and 4. A spring 6 is connected with one end of the bridle bar 5 and bears against an abutment 7, and serves to hold the point 3, normally in alignment with one of the rails of the track 1, as best 60 shown in Figure 2 of the drawings. A block and tackle device 8 is connected with the bridle bar 5, and the tackle is connected with levers 9 and 10, which are pivoted adjacent the track 1. A stop member 11 65 is located in the path of movement of the lever 10, and the spring 6 normally holds the lever 10 in engagement with the said stop member 11. A magnet 12 is positioned adjacent one end of the lever 10, and the magnet 13 is positioned adjacent one end 70 of the lever 9. The magnet 12 is larger and stronger than the magnet 13. Wires 14 connect the magnet 12 with conductors 17, which are extended along the track, 75 and which are supported upon poles 18, in a manner as shown in Figure 1 of the drawings. A current wire 19 is connected with the magnet 13, and may be connected with a generator (not shown). A wire 20 80 is connected at one end with the magnet 13, and at its other end with a circuit closer device 21. The said circuit closer is operatively connected with the lever 9. A wire 22 connects the circuit closer 21, with 85 the movable rail section 4, hereinbefore mentioned.

The cab of the locomotive, which travels upon the track 1 is indicated in the drawing at 23. Trolley arms 24 are mounted 90 at the opposite sides of the cab 23, and carry trolley wheels 25, which are adapted to encounter conductors 17, when the locomotive engine passes under the said conductors and is moving along the track 1 toward the 95 switch. A wire 26 connects the trolley arms and the trolley wheels with a generator (not shown), and which may be carried by the locomotive, or a car of the train which is being pulled by the locomotive.

The automatic railway switch has two 100 separate electric circuits, one for each of the electromagnets 12 and 13. The magnet 12 is energized for the purpose of swinging the lever 10, to throw the points 3 and 4. This magnet is energized by the electric current 110 from the generator which is carried by the

locomotive, or by a generator mounted at a fixed point. The trolley wheels, and trolley arms, which are mounted upon the locomotive, serve as means for closing the circuit to the magnet 12, when the wheels encounter the conductors 17. The magnet 13, when energized, serves as means for holding the points 3 and 4, at the position to which they have been thrown by the magnet 12. When the lever 10 is swung, the tackle 8 which is connected with both of the levers 9 and 10, swings the lever 9, whereby the gaps between the wires 20 and 22, is closed, by the circuit closer 21, and then the magnet 13 is energized by the current which flows over the wire 19 and which may come from a generator mounted at a fixed point. When the locomotive engine has passed beyond the conductors 17, the electric circuit to the magnet 12 is broken, but, inasmuch as the wheels of some of the cars are upon one rail of the switch and the point 14, the axles which connect the said wheels, bridge the gap between the point 4 and the rail of the switch, and the circuit remains completed to the magnet 13. When the last car has passed over the switch, a gap in the circuit, to the magnet 13 is made, and the said magnet is deenergized and the points 3 and 4 are returned to their normal position, under the influence of the spring 6.

Having described the invention, what is claimed is:

1. An automatic switch structure comprising in combination with a railway track, 35 a switch track, and movable points, spring means for holding the points at normal positions, a pair of levers pivoted adjacent the track, a magnet for each lever, a tackle for connecting the levers with the switch point moving means, means for energizing one of the magnets by a circuit completed by a vehicle moving upon the track, an open circuit connecting the other magnet with the switch and the movable point, and a circuit closer connected with one of the levers, and adapted to close the circuit to the second mentioned magnet, when the vehicle moves upon the switch, and the first mentioned magnet is energized. 50

2. An automatic railway switch, comprising pivoted points connected with the bridle bar, a pair of levers pivoted adjacent the switch, means operatively connecting the levers together and connected with the bridle bar, a magnet for each lever, one magnet being stronger than the other magnet, a circuit closer electrically connected with the weaker magnet and with one of the levers, the stronger magnet being connected with the conductors which are extended along the track and the weaker magnet being connected with movable parts of the switch. 55

In testimony whereof I affix my signature.

PERRY O. BROWN.
